(57) **CLAIM**

The ornamental design for a faucet, as shown and described.

DESCRIPTION

FIG. 1 is an isometric view of the faucet of the present invention shown from the upper right front;

FIG. 2 is a top plan view of the faucet illustrated in FIG. 1; FIG. 3 is a right side elevational view of the faucet illustrated in FIGS. 1 and 2, the left side being a mirror image thereof; FIG. 4 is a front elevational view of the faucet illustrated in FIGS. 1 through 3;

FIG. 5 is a rear elevational view of the faucet illustrated in FIGS. 1 through 4; and,

FIG. 6 is a bottom plan view of the faucet illustrated in FIGS. 1 through 5.

The broken lines in the Figures are for illustrative purposes only and form no part of the claimed design.
